(57) **CLAIM**

The ornamental design for a shoe midsole periphery as shown and described.

DESCRIPTION

FIG. 1 is a front perspective view of a shoe midsole periphery in accordance with my design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dash-dash broken lines shown in the drawings represent environmental structure in the form of the shoe outsole bottom and shoe upper as well as portions of the shoe midsole periphery that form no part of the claimed design.
